UNITED STATES PATENT OFFICE.

JOSEPH W. PEARL, OF PORTLAND, OREGON.

FOLDING SQUARE.

1,161,961.

Specification of Letters Patent.

Patented Nov. 30, 1915.

Application filed August 13, 1914. Serial No. 856,632.

To all whom it may concern:

Be it known that I, JOSEPH W. PEARL, a citizen of the United States, residing at Portland, in the county of Multnomah 5 and State of Oregon, have invented certain new and useful Improvements in Folding Squares, of which the following is a specification.

This invention relates to improvements in 10 squares such as are used by carpenters, millwrights and the like and has for its object to provide a square adapted to be folded so that the two members of the square, which when in use extend at right angles to each 15 other, when folded will be disposed adjacent to and parallel with each other.

Another object is to provide locking 20 means in a folding square of this character adapted to effectually lock the members in extended or folded position without presenting any objectionable projection upon either side of the square.

It is also one of the objects of this invention to provide means thereon for reading 25 any angle at which the members may be disposed.

I attain these and other objects, as will hereinafter appear, by means of the improvements illustrated in the accompanying 30 drawings in which,

Figure 1 is a front elevation of the square extended ready for use and also shows in broken lines an adjustment to an angle other than 90 degrees. Fig. 2 shows a front 35 elevation of the square folded. Fig. 3 is a detail front elevation of the head of the long member shown in the other views. Fig. 4 is a detail front elevation of the head of the short member of the square. Fig. 5 40 is an enlarged detail top plan view of the subject matter shown in Fig. 4. Fig. 6 is a detail top plan view of the subject matter shown in Fig. 3. Fig. 7 is a sectional top plan view through the center of the lock 45 slot and thumb recess, taken on the line A—A in Fig. 2.

Referring to the drawings, 1 designates the main or long member of the square and comprehends a flat rectangular blade having a semicircular dove-tailed recess at 2 50 and a projection at 3 so disposed that its edge which is beveled as at 4 completes another quarter circle coaxial with and contiguous to the outer edge of the recess 2. 55 The projection 3 and the recessed portion

are made one half as thick as the remainder of the blade.

The short, folding member of the square is designated as 5 and has a semicircular head or projection 6 with a beveled edge as 60 at 7 adapted to fit within the recess 2 in blade 1. The head 6 of the blade 5 is thinned to one half the thickness of the blade and dove-tail-recessed as at 8 to receive the edge 4 of the projection 3 of blade 1. The blade 65 5 is provided with a shoulder at 9 adapted to engage the edge of blade 1 at 10.

The two members 1 and 5 of the square are pivotally attached to each other as by a headed pin at 11 which passes through an 70 orifice 12 provided in blade 1 and an orifice 13 provided in blade 5.

To lock the blades either in extended or folded position a spring lock bar 14 is mounted in a recess 15 provided in the head 75 6 wherein it is attached as by a rivet 18 as shown and the blade 1 is notched as at 16 and 17 to receive the end of the lock bar which extends slightly beyond the edge of the head 6. A thumb recess 17^a is provided 80 adjacent notch 17 so that the lock bar 14 may be released therefrom more easily.

If desired the lock-bar 14 may be provided with an index mark as at 19 adapted to register with graduations which are provided upon blade 1 at 20 so as to provide 85 means for ascertaining the angle of the blades to one another when used as a bevel square.

It is obvious that a folding square of this 90 character may be graduated the same as any non-folding square of similar proportions.

What is claimed is:—

1. A folding square comprising a blade having a dove-tailed circular recess in one 95 end, another blade having a circular head with beveled edge adapted to fit within said recess and pivotally mounted therein, one of the blades being provided with notches adjacent its circular edge and a spring lock 100 bar mounted in the other blade so as to engage any one of the notches for the purpose of locking the blades in the desired positions.

2. A folding square comprising a blade 105 having a circular recess in one end, another blade having a circular head adapted to fit within said recess and pivotally mounted therein, one of said blades being provided with notches adjacent its circular edge, a 110

spring lock bar mounted in the other blade so as to engage any one of the notches in the other blade for the purpose of locking the blades in the desired position, one of said blades being provided with graduation marks adjacent the circular edge thereof, and said lock bar being provided with an indicating mark to coöperate with said

graduation marks for ascertaining the angle of the blades toward one another.

10

In testimony whereof I affix my signature in the presence of two witnesses.

JOSEPH W. PEARL.
